UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed January 22, 1924. Serial No. 687,751.

To all whom it may concern:

Be it known that I, FRED S. CARR, a citizen of the United States, and resident of Newton, in the county of Middlesex, State of Massachusetts, have invented an Improvement in Fasteners, of which the following description, in connection with the accompanying drawings, is a specification, like characters on the drawings representing like parts.

This invention aims to provide an improved fastener peculiarly well adapted for securing rugs and the like, an improved method of securing the sockets of such fasteners to rugs, and an improved attachment of rugs to floors, and this application is a continuation in part of my application Serial No. 616,292 filed February 1, 1923, entitled "Fasteners."

20 In the drawings, which illustrate a preferred and a modified form of my invention:

Figure 1 is a plan view of a portion of a rug or carpet showing in dotted lines the position of an underlying fastener;

Fig. 2 is a plan view of the socket, showing the attachment of the prongs to the somewhat magnified warp and weft threads;

Fig. 3 is a plan view of the socket before attachment to the ring;

Fig. 4 is a section on the line 4—4 of Fig. 3;

Fig. 5 is a section on the line 5—5 of Fig. 1, being partly in elevation;

Fig. 6 is a plan view of a modified form of socket before attachment to the carpet; and

Fig. 7 is a section on the line 7—7 of Fig. 6.

Referring to the drawings, in the preferred form of my invention selected for illustrative purposes and shown in Figs. 1 through 6, I have provided a stud having a head 11 and a screw portion 9 secured to the floor 13 of an automobile or room. The head 11 of the stud is entered in a socket including a bottom plate 15 providing a stud-receiving aperture and surrounded by an upstanding wall 17, thereby providing a recess for a stud-engaging spring 19 and a spring-securing plate 21 which overlies and holds in place the stud-engaging spring 19, this plate 21 also apertured to allow

passage of the head of the stud therethrough. The spring-securing plate is held in position by inwardly bent lugs 23 (best shown in Fig. 3) struck inwardly from the upstanding wall 17. As the wall 17 is somewhat weakened by the removal therefrom of the material providing the lugs 23, I have provided above the wall a continuous ring 24, integral with the wall 17 and bottom plate 15, this ring preferably generally parallel to the bottom plate 15 and providing a buffer surface of substantial width to prevent cutting of the warp and weft of the carpet thereagainst in use.

Carpet fasteners are particularly likely to become filled with dust, which interferes with the action of the spring, rendering a considerable pull on the carpet necessary to separate the socket from the stud. Thus a peculiar problem arises in providing a strong, and at the same time slightly and inexpensive, attachment of the socket to the carpet or rug. To fasten the socket to a carpet or rug 25, I have provided a series of prongs 27, extending upwardly from the periphery of the ring 24, these prongs adapted to pierce the carpet or ring. Following my improved method of attaching the socket to the rug, these prongs after penetrating the warp and weft are bent outwardly, preferably curvilinearly so that they are arched and so that the outer ends thereof extend downwardly through the web of the carpet. Thus web-engaging hooks are provided corresponding to the upper side of a stitched loop, and the fastener is in effect metallically stitched to the warp and weft of the carpet. The metallic outwardly extending curved loop or hook has, however, marked advantages over a flexible loop such as is provided by ordinary stitching with thread or even wire, because when upward strain is exerted on the carpet to separate the socket from the stud, the strain on the carpet pulls against the inner curved surface of the metallic loop, as though strain were exerted against the inner surface of a hook. Thus the harder the strain the more secure is the engagement, up to the point of breakage of the warp and weft threads. This is not the case when the metallic prongs are bent inwardly, instead of

90

95

100

outwardly, as in the former the strain tends to pull the warp and weft out of the metallic loops.

The pile of the carpet is not overlain to any substantial extent by the prongs, and the prongs are to a large extent concealed by the pile, where the latter is of substantial length. Aside from this, the relatively small portions of the prongs above the warp and weft threads are so embedded in and surrounded by the pile, that they are to all intents and purposes concealed, even when first applied. Ordinarily the prongs become entirely unnoticeable when, after a short period of use, sufficient dirt accumulates above them to obscure the sheen of the metal. The prongs, extending outwardly from the casing, enlarge for any given size of casing the area of the carpet web or backing embraced within the prongs, thus distributing over a considerable area of the web, that strain to which it is subjected when the carpet is pulled to disengage the socket from its cooperating stud.

The zone of engagement of the prongs with the carpet web, being relatively far removed from the stud-engaging spring 19, provides a favorable leverage when strain is exerted on the carpet to separate the socket from the stud, thus reducing not only the strain on the prongs but, more important, greatly reducing the strain on the carpet web or backing, as compared with socket-attaching systems wherein the engagement between the socket and the web practically overlies the stud-engaging spring 19.

While for some purposes, the outwardly thrown prongs need not be curved, there are in most instances decided advantages that they be curved. Where they are curved the strain on the prong arising from a fastener disengaging pull on the carpet is necessarily transmitted to portions of a prong or several prongs, relatively close to the body of the fastener so that the prongs will not be bent by the strain. When, on the other hand, the prongs are bent straight outwardly, any fastener disengaging strain on the carpet is applied to the extreme outer end of the prongs, and the leverage is such that there is a very strong tendency for the prongs to be bent upwardly and to release their hold on the carpet. The curved prong, on the other hand, is so strong that the attachment is fully as secure as though a separate attaching washer or ring were provided. In an outwardly bent prong, the engagement between the prong and the warp or weft threads when under strain is always at a relatively wide portion of the prong, so that a substantial bearing surface is provided against these threads, minimizing any tendency to cut them.

The amount of the pile overlain by the

curved prong is much less than that overlain by a corresponding prong bent straight outwardly, and therefore the outwardly curved prong has the additional advantage of being the more completely concealed by the pile.

Referring to Fig. 5, it will be seen that the side wall 17 extends downwardly past the plane where the spring 19 engages the neck of the stud and that the lowermost face 15 of the socket may contact with a rigid supporting surface beneath the carpet. In the present instance it is shown as seating on the flange of the stud 11 which in turn rests on the floor so that the socket is immediately supported on the floor 13.

One of the principal strains exerted on the fastener in use is a lateral strain substantially in the plane of the floor or the carpet such as is produced by sliding or scuffing the foot over the surface of the carpet. Now, if we imagine a pull such as would be produced in this manner exerted substantially in the plane of the carpet and towards the left in Fig. 5, it will be seen that the face 15 of the socket at the left in that figure seats on its rigid support and cannot move further downwardly to permit the socket as a whole to tip and be disengaged by such tipping action from the stud. On the other hand, if it is desired intentionally to release the fastener, the edge of the carpet is raised and pulled upwardly and if the right hand edge in Fig. 5 is so raised, it will be seen that the seated surface of the socket at the left will form a fulcrum about which such tipping movement is permitted, thus providing for a quick and easy release of the fastener. In this action the out-bent prongs, being disposed relatively far from the fulcrum, provide a favorable leverage for such movement. This will perhaps be better visualized by imagining the carpet lifted at the left hand side of Fig. 5 since the prong 7 appears in full lines on that side in the figure.

The side wall 17 adds greatly to the strength of the socket as a whole, and also strengthens the prongs at the periphery of the ring portion 24 by providing a very strong peripheral portion adjacent the prongs so that the weight of a person stepping upon the carpet or ring directly over the concealed socket will not crush the socket casing, the bending, if any, merely deflecting the prongs into even more firm engagement with the carpet web or backing.

Referring now to the modified form of socket which I have shown in Figs. 6 and 7, the socket casing 33 is formed the same as in the preferred form of plate (shown in Figs. 1 through 6), except that the stud-engaging spring 35 is held within the casing by lugs or prongs 37 integral with the casing, struck upwardly and bent over the

spring 19, as best shown in Fig. 6. This construction provides a two-piece socket instead of a three-piece socket as shown in the preferred form, the attachment to the rug 5 in this form of construction preferably being, as illustrated, the same as previously described in connection with the preferred form.

While I have shown and described a preferred form of fastener (with one modification thereof), and a preferred attachment thereof to a carpet, and while I have described a preferred method of effecting this attachment, it will be understood that I have 10 done so for purposes of clarification, but that for some purposes reversal may be desirable in that the stud instead of the socket may be attached to the carpet in accordance with my invention, and that other considerable changes may be made without departing from the scope of my invention, which is 15 best defined in the following claims.

Claims:

1. A carpet fastener socket installation 25 comprising a casing underlying the back of a carpet and presenting upstanding prongs which penetrate the carpet backing and extend outwardly over the carpet web, said prongs being concealed by the pile of the 30 carpet.

2. A carpet fastener socket casing having a plurality of attaching prongs penetrating the carpet web and extending outwardly from the socket to engage over the carpet 35 web, said prongs curved and having their outer ends extending downwardly through the web to provide a hook-like engagement, localizing near the base of the prongs and strain arising from upward pull on the 40 carpet when the socket is being disengaged from a cooperating stud.

3. A carpet fastener comprising, in combination, a stud part and a socket part, one 45 of said parts having attaching prongs penetrating the carpet web and extending outwardly to engage over the carpet web, said prongs curved downwardly toward their outer ends and extending back through the web to provide a hook-like engagement 50 therewith minimizing bending strain on the prongs and minimizing the opportunity for slippage of the warp and weft threads from under the prongs, when the carpet is pulled upwardly to disengage the stud and socket.

55 4. A carpet fastener socket having contractile and expansible means adjacent to the bottom thereof adapted to engage and disengage an underlying stud secured to the floor, said socket presenting upstanding 60 prongs adapted to penetrate the carpet back and be bent outwardly over the warp and weft threads thereof, the entire socket, except for the bent-over parts of the prongs, being located beneath the carpet.

65 5. A carpet fastener socket comprising a

casing and upstanding prongs integral with and arising from the periphery of said casing, said prongs bent outwardly and downwardly over the warp and weft threads of the carpet so that an upward pull on the carpet tends to hold the socket more firmly to the carpet.

6. A carpet fastener socket having a casing presenting upstanding prongs bent outwardly and downwardly to provide hooks 75 over the web of the carpet, said hooks concealed from view by the pile of the carpet.

7. A carpet fastener socket having a casing presenting upstanding prongs bent outwardly and downwardly to provide hooks 80 over the web of the carpet, said prongs pointed to minimize cutting of the web threads, and widening toward said casing whereby, when upward strain is exerted on the carpet, the web threads will be pulled 85 against relatively wide portions of said prongs, relatively close to said casing.

8. A carpet fastener socket comprising, in combination, a dish-shaped casing having a peripheral strengthening wall, a spring for 90 engaging a stud and spring-positioning means for positioning said spring relative to said casing, prongs projecting from the periphery of said casing and curving upwardly, outwardly and downwardly, thereby providing hooks engaging over warp and weft threads of the carpet.

9. A carpet fastener socket comprising a casing having a plurality of fabric-engaging 100 prongs, and a resilient stud-engaging member secured in operative relation to said casing, said prongs clenched outwardly and downwardly into engagement with the warp and weft threads of said fabric.

10. A carpet fastener socket, comprising a prong-presenting member and a resilient stud-engaging member secured to said prong-presenting member, said prongs 105 piercing a carpet or the like and thereafter bent hook-shaped into engagement with and over the warp and weft threads of said carpet with the pointed ends directed toward the carpet back and the hooks concealed from view by the pile thereof.

11. A carpet fastener socket comprising a contractile and expansible stud-engaging member, a support for said stud-engaging member and a plurality of prongs spaced about the periphery of said support, said prongs piercing a carpet or the like and thereafter bent outwardly and downwardly to form hooks for engagement with the warp and weft threads of said carpet.

12. A carpet fastener comprising a stud 125 adapted to be fastened to a floor, and a socket presenting a casing having a body part presenting a stud-receiving aperture, a circular spring behind said stud-receiving aperture and a spring retaining part overlying said spring and secured within 130

said body part, one of said parts presenting integral prongs to penetrate the web of a carpet, said prongs projecting from that side of the socket opposite said stud 5 receiving aperture.

13. A carpet fastener comprising a stud adapted to be fastened to the floor and a socket for engaging the stud adapted to be secured to the carpet, said socket member 10 presenting a casing having upper and lower parts enclosing a spring, the upper part housed within the lower part and upwardly projecting carpet engaging prongs on the lower part.

15. 14. A fastener socket secured to a fabric having a warp and presenting prongs penetrating the warp from the back and deflecting outwardly and downwardly to engage portions of the warp more widely separated 20 than the over-all diameter of the socket proper.

15. A snap fastener socket for carpets and the like comprising a casing having a bottom portion, a peripheral wall above 25 said bottom portion and prongs forming a continuation of said peripheral wall, said casing containing a spring and providing above said spring a top plate, said prongs deflected outwardly and downwardly to 30 embrace portions of the warp of the carpet, whereby an upward pull on the carpet on any side will exert force on the warp away from the end of the adjacent curved prong and prevent disengagement of the prongs from the web.

16. The method of securing to a carpet a fastener socket presenting a body portion having a stud-receiving aperture therein and upwardly projecting prongs, which 40 comprises initially locating said socket back of the continuous web of the carpet with the prongs projecting toward the web then forcing said prongs through the web of the carpet and bending said prongs outwardly 45 to overlie the web on the opposite side thereof from the body portion presenting the stud-receiving aperture, the body of the socket being entirely located back of the web.

50. 17. The method of attaching a carpet fastener having at its periphery a plurality of upwardly projecting prongs to a carpet or the like, having a web and a pile, which comprises forcing said prongs through the 55 web and bending said prongs curvilinearly outwardly and downwardly to form hooks and to a substantial extent concealed by the adjacent pile of the carpet into which the warp and weft threads forming the web are pulled when strain is exerted on the carpet to separate the socket from a cooperating stud.

60. 18. The method of attaching a carpet fastener socket having a body provided with 65 a plurality of prongs to a carpet or the

like which comprises forcing said prongs through the web of the carpet and deflecting said prongs curvilinearly outwardly and downwardly to form hooks over threads of said web, while said prongs adjacent their 70 ends again penetrate the web, whereby an upward pull on the carpet, resisted by the engagement between the socket and a co-operating stud, will pull the engaged threads of the web further into the hooks and locate the strain on the prongs at points relatively close to the body of the socket.

19. A carpet fastener comprising a socket element having a plurality of attaching prongs bent outwardly and downwardly into 80 hook-like engagement with the carpet web and concealed by the pile, said socket having a stud-receiving opening and having provision for resiliently engaging a stud entered in said opening, and further having a wall disposed outwardly of said opening to seat on a support beneath the carpet to oppose such tipping of the socket relative to the stud as would effect disengagement 85 of the socket from the stud when lateral strain is exerted upon the carpet.

20. A carpet fastener comprising a socket element having a plurality of prongs bent outwardly and downwardly over the carpet web and concealed by the pile, said socket 90 having a stud-receiving opening and having provision for resiliently engaging a stud entered in said opening and further having a wall positioned between said prongs and said opening to seat on a support beneath 95 the carpet to oppose such tipping of the socket relative to the stud when lateral strain is exerted upon the carpet as would effect disengagement of the socket from the stud while providing a fulcrum against the underlying support about which the casing may be tipped when the carpet is pulled upwardly at one side of the socket, said prongs 100 providing a favorable disengaging leverage 105 for application of force at a point relatively remote from such fulcrum to spring the socket free from the stud.

21. A carpet fastener element for separable connection with a cooperating snap-fastener element secured to the floor comprising a part for engagement with said cooperating element, a surrounding elevated body portion and attaching prongs extending from said body portion and bent outwardly and downwardly over the carpet web 115 and concealed by the pile, said elevated portion seating on a support beneath the carpet to oppose such tipping of the element relative to said cooperating element as would effect disengagement of the two when lateral strain is exerted upon the carpet.

In testimony whereof, I have signed my name to this specification.

FRED S. CARR.
